(57) **CLAIM**

The ornamental design for a mitt, as shown and described.

DESCRIPTION

FIG. 1 is a front perspective view of the present invention. FIG. 2 is a front elevation view of the design as shown in FIG. 1.

FIG. 3 is a rear elevation view of the design as shown in FIG. 1.

FIG. 4 is a left side elevation view of the design as shown in FIG. 1.

FIG. 5 is a right side elevation view of the design as shown in FIG. 1.

FIG. 6 is a top plan view of the design as shown in FIG. 1; and, FIG. 7 is a bottom plan view of the design as shown in FIG. 1. The dashed broken lines in FIGS. 1-7 indicate disclaimed matter and no claim is made thereto. The disclaimed matter includes the zig-zag stitching shown in dashed lines, the seam lines shown in dashed lines, and the portion of the mitt below the claimed border identifier.

The present invention is a design for an oven mitt.
